HEADLIGHT CONTROLLING DEVICE

William Farquhar Fraser, Victoria, British Columbia, Canada

Application May 16, 1934, Serial No. 725,937

1 Claim. (Cl. 240—41.61)

This invention relates to a headlight controlling device for automotive vehicles, its object is to promote driving safety to all concerned by providing a positive and instantaneous method whereby the headlight or both of them may be angularly diverted from the straight and forward direction left or right-handedly, and particularly the latter, so that the blinding glare offered to an oncoming vehicle is instantly removed, and the light ray automatically directed upon the curb or edge of the road where it is urgently needed for the proper guidance of the driver. By this procedure the sudden shift of the headlight rays afford to the approaching vehicle a live and arresting signal, whilst at the same time the origin of the light ray provides a clear and easily viewed signal as to what must be avoided during the passage of the two vehicles to escape contact.

I am aware that various dirigible headlight devices have been suggested. Some with universal angular tilting mechanisms, others interconnected with the steering gear, but so far as I am aware none with the same positive, and instant deflection of the reflector which my device provides.

In carrying my invention into effect I adopt for the reflector within the lantern, an angular movement in the horizontal plane to a stop, at which point the reflector is automatically locked until released by the driver. The reflector swivels on a vertical axis and is motivated by a small electric motor within the lantern, and through a rack and pinion connection controlled by a press switch on the control board, or means equivalent to these.

By this combination it will readily be seen that I am able to obtain an absolutely prompt but steady and uniform motion, which is entirely devoid of jerks and shocks which invariably break the lamp filaments just at the moment when their failure is most risky or dangerous. In more fully describing my invention reference is made to the drawing which accompanies and forms a part of this application and in which

Fig. 1 is a vertical section through the centre line of the reflector and lantern,

Fig. 2 is a part plan view to an enlarged scale, and shows more particularly the revolving and arresting gear, with the stabilizing device for recentering the reflector superposed in broken lines,

Fig. 3 is an elevation of the magnetic stop, and

Fig. 4 is a diagram of the electric connections.

It is not intended that the drawing should be limitative as regards mechanical details, except

insofar as such may fall within the scope and language of the claim.

In the drawing the numeral 5 indicates a headlight reflector of the usual parabolic type, 6 the lamp bulb for same, 7 the lantern or casing secured to the chassis in the usual way. 8 is a vertical pivot spindle in two parts axially coincident, and secured to the reflector above and below and running in anti-friction bearings 9 secured in the casing 7. A small electric motor 10 mounted in the lower portion of the lantern 7 actuates the angular movement of the reflector 5 through the pinion 11 and the arcuate rack 12, the swing of the latter being utilized to actuate the blade 13 of the switch 14 so as to open the circuit 15 of the motor 10, and thus arrest the angular motion of the reflector 5 at the limit of its swing. Slight further movement of the blade 13 contacts the terminal 16 thus closing the circuit 17 of the magnetic clutch 18. This raises the hook extremity 19 of the hinged armature plate 20 whereby the latter engages the arm 21 of the toothed sector or arcuate rack 12 which is thereby held until the circuit 17 is opened when the hook 19 and the plate 20 fall by gravity. This action then permits the reflector 5 to respond to the tension of the centering spring 22 of the stabilizing device indicated in broken lines in Fig. 2. This latter consists of a stop pin 23 against which the two notched pivotal arms 24 firmly abut under the tension of the spring 22, either of the arms 24 being extended against the tension of the spring 22 by the roller ended crank 25 secured to the spindle 8 of the reflector 5.

The operation of the device is readily seen from the figures and the diagram indicated in Fig. 4. It is assumed that the headlight is pointing direct forward and that the reflector is to be swung over to the right. The switch 26 is closed and current flows from the battery 27 to the switch blades 13 thence through the contacting terminal 28 to circuit 15 through motor 10 to ground at 29. This energizes the motor to turn the rack 12 angularly clockwise until the blade 13 is contacted by the stop 30 on the rack 12 thereby opening the motor circuit 15. Slight further movement of the rack 12 contacts the terminal 16 closing circuit 17 operating clutch 18 which holds the rack until switch 26 is again opened when the rack 12 is released and the stabilizing device by the spring 22 centralizes the reflector and steadies it to its normal position.

I claim:—

In a dirigible headlight device having a reflector pivotally mounted in a lantern and mov-

able in a substantially horizontal plane in combination a vertically disposed pivot spindle secured to the lower external surface of the said reflector and a corresponding and axially coincident pivot spindle secured to the upper surface of the said reflector, antifriction bearings for the ends of said spindles and secured in said lantern, a toothed sector secured to one of said spindles, an electric motor secured in said lantern and 10 provided with a pinion engaging said sector, a pin stop secured in said lantern, a pair of divergent arms pivotally secured in said lantern and a helical extension spring between and connected to said arms whereby the latter oppositely 15 abut the said stop at their outer extremities, a

lever arm secured to one of said pivot spindles between said divergent arms and adapted to engage by its outer end either of the inner edges of said divergent arms and disengage it from abutting the said stop against the tension of said spring whenever said reflector is moved from its central position, magnetic clutching means for engaging and holding said toothed sector at the limit of its angular motion, and switching means operated by said toothed sector whereby 10 when said reflector has reached its angular limit the electric circuit of said motor is opened and the circuit of said magnetic clutch is closed. 5
